UNITED STATES PATENT OFFICE.

LOUIS V. ARONSON, OF NEWARK, NEW JERSEY.

TOY.

Application filed August 11, 1925, Serial No. 49,544.

The invention relates to toys, and has as an object the provision of a sparking toy which may be repeatedly operated with rapidity.

5 A further object of the invention is the provision of a sparking toy that may be caused repeatedly to produce a shower of sparks by means of a crank.

10 A further object of the invention is the provision of a toy which may be caused to produce a shower of sparks by means of a crank and which may be mounted in a casing to simulate a machine gun or other rapid fire arm.

15 Further objects of the invention will appear from the following description when read in connection with the accompanying drawing, wherein

20 Fig. 1 is a side elevation of the mechanism having a possible form of casing and support shown in dotted lines;

Fig. 2 is a vertical transverse section on lines 2—2 of Fig. 1 of the mechanism and supporting plate; and

25 Figs. 3 and 4 are like views respectively, taken on lines 3—3 and 4—4 of Fig. 1.

As shown, the device comprises a supporting plate 10 having a cam shaft 11 journaled therein.

30 A plate 12 is supported upon the plate 10 as by means of columns 13, engaged by screws 14 and 15.

The plate 12 is utilized in the form shown, as a second journal for the cam shaft 11.

35 Fixedly secured upon the cam shaft 11 there is shown a cam 16 having a hub 17 with a reduced portion 18 surrounding the shaft 11 and forming the exterior of the journal in the plate 12.

40 To produce sparks, there is shown an abradant wheel 19 having an abradant surface 20 at its periphery and formed with a pinion 21 integral therewith or fixedly secured thereto.

45 A pyrophoric element 22 is shown spring-pressed against the abradant surface 20 as by means of a U-shaped rod 23, having a spring 24 adjustably abutting against the knurled nut 25 and having an abutment 50 against the loop 26, which forms a guide for movement of the rod 23.

A support for the rod 23 and the abradant wheel 19—20 is shown as provided in the form of a single plate 27, having a portion 55 thereof turned into a cylindrical pyrophoric element holder 28, second portions 26—29

turned at an angle and perforated as a guide for the rod 23, and an abutment for the spring 24, and other portions 30, 31, 32 turned outwardly as supports to hold the 60 plate 27 in spaced relation to the plate 10.

The spacing lugs 30, 31, 32 have reduced portions on their extremities that are passed through openings in the plate 10 and clinched.

65 To operate the pinion 21 there is shown a rack bar 33 having rack teeth 34, adjacent one end thereof and guided in its reciprocation by an elongated slot 35 reciprocating upon a portion of the hub 17 of the cam 16. 70

A coiled spring 36 is shown anchored at 37 to the plate 27 and fastened to the rack bar 33 as at 38.

To cause movement in one direction against the tension of spring 36, there is 75 shown a projection 39 preferably equipped with an anti-friction roller 40 projecting into the path of progression of the cam 16.

To cause rotation of the cam 16 a crank 41 is mounted upon the shaft 11.

80 A casing of any desired character may be provided within which the plate 10, having the mechanism mounted thereon, is mounted. A possible form for this casing is illustrated in dotted lines in Fig. 1 and is intended to 85 simulate a machine gun in outward contour.

In operation, the roller 40 normally stands in the position shown in Fig. 1. Rotation of the crank 41 will cause the roller 40 to ride upon the cam 16, the cam 16 being rotated 90 in the direction shown by the arrow. This action of the cam will cause a retraction of the rack bar 33 accompanied by a slow movement of the abradant wheel 19, which, because of the low speed of such movement, 95 will not cause sparks to be emitted. When the point 42 of the cam has been passed by the roller 40, sudden release of the rack bar will cause the same to move quickly forward under tension of the spring 36 and will 100 therefore produce a shower of sparks by friction upon the pyrophoric element 22.

105 Minor changes in the physical embodiment of the invention may be made within the scope of the accompanying claims without departing from the spirit thereof.

I claim:

110 1. A toy comprising, in combination, a casing formed to simulate a machine gun, light-emitting means within the casing adjacent the muzzle thereof, a reciprocable element for intermittent operation of said

- light-emitting means having a slot therein, a shaft journaled in said casing adjacent the rear thereof and passing through said slot, a crank carried by said shaft exterior of the casing for its operation, a cam rigidly mounted upon said shaft within the casing, and means carried by said reciprocable element coacting with the cam for causing reciprocation of said element.
- 10 2. A toy comprising, in combination, a support, a sparking apparatus supporting plate mounted upon and spaced from said support, a wheel journaled in said plate having an abradant surface and a pinion formed upon its periphery, means mounted on said plate to hold a pyrophoric element, other means upon said plate to apply spring pressure upon said element whereby to press the same against said abradant surface, a reciprocable rack bar coacting with said
- pinion, a revolute cam journaled on said support to cause reciprocation of said rack bar, and means to cause revolution of said cam.
3. A toy comprising, in combination, a support, pyrophoric spark producing means mounted upon said support, a reciprocable element to actuate said means and having an elongated slot, means projecting from said reciprocable element, a revolute cam journaled upon said support, a hub upon said cam passing through said slot, said cam coacting with said projecting means to cause retraction of said reciprocable element upon revolution of the cam, spring means to return said reciprocable element to normal position upon release by said cam, and means to cause revolution of the said cam.

LOUIS V. ARONSON.
